UNITED STATES PATENT OFFICE.

BENJAMIN C. VANDUZEN, OF CINCINNATI, OHIO, ASSIGNOR TO HERBERT D. LAFFERTY, OF NASHVILLE, TENNESSEE, AND STANLEY B. LAFFERTY, OF DAVENPORT, IOWA.

PUMP..

SPECIFICATION forming part of Letters Patent No. 268,843, dated December 12, 1882.

Application filed May 26, 1882. (No model.)

To all whom it may concern:

Be it known that I, BENJAMIN C. VANDUZEN, of the city of Cincinnati, in the county of Hamilton and State of Ohio, have invented certain new and useful Improvements in Pumps, of which the following is a specification.

My invention relates to that class of pumps known as "double-acting force-pumps," and has reference in general, first, to the construction of the standard and of the base, and, secondly, to the construction and arrangement of the pump cylinders and valves, to enable the various valves to be readily removed from the well for examination, repairs, and replacement.

The various features of my invention will be obvious from the following description and the drawings, in which latter—

Figure 1 is an elevation, partly in section, of a pump embodying the principles of my invention. Fig. 2 is an elevation of the body of the pump, taken on a plane at right angles to Fig. 1, the base or bed piece at the lower portion of the standard being shown in section. Fig. 3 is a sectional view taken at the line 1 1 of Fig. 1. Figs. 4, 5, 6, and 7 are enlarged sectional views taken respectively at the line 2 2, 3 3, 4 4, and 5 5. Fig. 8 is an enlarged view of a central vertical transverse section of the lower valve and its connections.

A indicates the standard of the pump, which is made of metal, and preferably cast in one piece, and may be ornamented to suit the taste of the manufacturer. The upper end of this standard is provided with the brackets or ears a, between which the handle A' is pivoted. Near the middle of the body is a globular enlargement, a', from which projects the spout A². The interior of this globular enlargement communicates with the spout, but is separated from the interior of the upper part of the standard (which is preferably made hollow for the sake of lightness) by a partition, so that the water cannot extend up in the standard beyond the enlargement a'. The interior of the body is provided at a point just below the enlargement a' with an interior flange, into which is screwed the upper end of the discharge-pipe

B in such a manner that the water passes through the discharge-pipe and into the enlargement a' and directly out through the spout. The lower end of the body has a circular tapered foot or extension, B', which, when the pump is in position, fits into a circular cup, b, formed in the base C, and is firmly held therein. The taper on the standard of the pump and the reverse taper on the cup allow the standard to be firmly wedged to the base, and, as a precautionary means for preventing the standard from working loose from the bed-piece C, the bolts b' are employed, passing through the bottom of said cup and through the bottom of said foot, as shown in Fig. 2. The base of the standard above the taper is provided with a flange, b², which overlaps and protects the edges of the cup. The joint between the bed-piece is thus elevated above the curb, and is out of the way of snow and ice and water. The bolts b', being in the position already mentioned, are hid, and the bolt-holes are in a position that no rain and none of the water or other liquid coming from the spout or spilt from any vessel placed over or upon the curb or running down the body A of the pump can pass through them. This base, besides the cup b, is provided with an opening, D, through which certain of the parts below are lifted when they are removed from the well, and the opening D is provided with a cover, d, through which the pump-rod D' passes. The base C is provided with a surrounding flange, C', by which it is secured to the curb. This extension of the base is elevated for the same purposes for which the first-mentioned part of the base is elevated, and also effectively braces the standard from lateral deflection and contributes to firmly secure the standard in position.

The discharge-pipe B passes down from its connection at the enlargement a' through the body and the base C into the well, and to the lower end of said discharge-pipe is connected the larger cylinder E, the pipe B being screwed into the projection e extending from the side of the cylinder, the projection being braced and strengthened by a web, e'. Through this projection e passes the conduit-way E', by which

the cylinder E communicates with the discharge-pipe B. The cylinder E extends a short distance above the projection e, and its upper end is provided with a flaring mouth 5 larger than the diameter of the cylinder, and into the flaring mouth fits the upper and smaller cylinder, F. Near the center of this cylinder F is a surrounding collar, f, around whose periphery is a packing-ring, g, of elastic material. This collar fits into the flaring mouth of the cylinder E, and the packing g forms a tight joint between the two cylinders. The cylinder F, whose outer diameter is less than the inner diameter of the cylinder E, extends 15 down into said last-named cylinder to a point just above the passage E', and the lower end of the cylinder F is provided with an open flange or a number (preferably three) of lugs, g', which fit against the inner face of the cylinder E, and by this means the cylinder F has two bearings within the cylinder E, and is thus held more firmly in position and in line with cylinder E. The interior of the cylinders being smooth and usually lined with porcelain 25 or other glazing substance, the packing g forms a perfectly-tight joint between the inner face of the cylinder E and the cylinder F. The cylinder F is provided with a lateral projection, G, which is provided with a passage-way, which 30 terminates in an opening, h, passing through the collar f and communicating with the air-space S between the cylinders. Into the upper side of this hollow projection G is screwed the lower end of the pipe H, which serves as 35 an air chamber, and also as a rod for holding the cylinder F firmly in position with relation to the cylinder E, and as a support for the clamps for guiding the actuating-rod D', and as means for withdrawing the upper cylinder, 40 F. The bottom of the cup b in the base C is provided with a lug or projection, i, through which passes a set-screw, I, which latter may be caused to bear against the upper end of the pipe H. The set-screw thus holds this pipe 45 H, and through the intermediate agency of said pipe H holds the cylinder F in position.

The cylinders F and E are located directly under the opening D in the base C, and in these cylinders are located the plungers J J', 50 connected to the pump-rod D'. These plungers are connected to each other and to the pump-rod by means of a bolt or rod, j, said rod being connected to the pump-rod and passing through a tube, cage, or frame-work, j', 55 and finally through the lower plunger, J', a nut being screwed onto the end of the rod, by which means the two plungers are united. The lower plunger consists of two metal plates or disks, K, each provided with a series of 60 openings, k, as shown in Fig. 6, a ring, L, of leather or other flexible material, being clamped between the two disks, the outer edge of the leather or flexible material being turned up, as shown in Fig. 1, to form the packing for the 65 piston. Above the disks K is a circular flexible valve, M, which permits the water to flow

upward through the openings k, but prevents any backward flow of water.

In the bottom of the cylinder E is placed a valve, N, which prevents any return of water 70 from the cylinder E to the suction-pipe O, screwed into the bottom of said cylinder. This valve N is secured to a ring, N', which is provided with an arch or equivalent projection, N², preferably located above the valve, as 75 shown. In the center of this arch is a hole, n, which is provided with a female screw-thread. The purpose of this construction is to afford a ready means for removing the valve from the cylinder E when it is desired to examine or 80 repair or replace it. The lower end of the pump-rod j is provided, as shown, with a screw-thread. When desired, this end of the pump-rod j may have the female screw, and the arch or projection N² have a screw-threaded stud 85 or teat, the thread of which stud or teat, when the rod j is lowered, shall engage the female screw of the rod j, or the nut connected therewith, when the latter is properly turned. When this valve N is to be removed the pump-rod D' 90 is disconnected from the handle A'. The pistons with rod j will then drop down until the end m of the rod j enters the hole n in the arch N², and by turning the pump-rod this end is 95 attached to the pump-rod, and may be lifted from the well with the pistons.

The lower end of the cylinder E is shaped as shown in Fig. 1, being somewhat contracted, as shown at R, and into this contracted 100 portion fits the ring N', to which the valve N is connected, an elastic packing, R', being interposed between the ring N' and the inner face of the contracted portion of the cylinder E. The shoulder between the contracted portion R and the remainder of the cylinder E is, as shown at t, rounded, and below this shoulder is a straight portion, t'. The lower end or margin of the ring N' is also preferably rounded, and the packing R', fitting into an annular chamber around the outer face of the ring, is shaped to fit the contracted portion R of the cylinder. Preferably, instead of the packing R' being so shaped, the construction of the ring N' and of the packing R' is as shown in 110 the drawings—viz., the periphery of the annular recess S' in the extension N' of the valve is made to correspond in shape with the interior shape of the contracted portion R of the cylinder. An elastic ring of packing, of the 115 same and proper thickness throughout, is then placed in said recess, and the packing will conform to the shape of said periphery. When the ring N' and packing R' are constructed in either of the forms hereinbefore mentioned the 120 ring is without difficulty guided into its seat at the bottom of the cylinder, and the packing R' forms a perfectly-tight joint.

An adjustable bracket, P, is connected to the pipe H, which bracket forms a steady support for the pump-rod, which passes through the free end of said bracket, as shown in Fig. 130

1. This bracket consists of two halves, p p' , the inner face of each of which, near the end which forms the support for the pump-rod, is provided with a lug, q , and a bolt, Q . The latter, passing through both of said halves p p' , causes them to firmly clamp the pipe H , the lugs q preventing the pump-rod from also being clamped. This adjustable bracket may be raised or lowered and secured in the desired position on the pipe H . Instead of being clamped on the pipe H , the bracket may be clamped to the discharge-pipe B , and will necessarily be clamped to the last-named pipe when the pipe H is omitted, as will sometimes be the case.

2. The upper cylinder, F , extending, as described, for some distance into the upper end of the cylinder E , and being provided with the collar f , an air chamber or space, S , is formed around the lower end of the cylinder, and the pipe H communicating with this air-space, a double air-chamber is formed.

3. If desired, a solid rod may be substituted for the pipe H , and in this event the space around the lower end of the cylinder F will serve as an air-chamber and produce an uninterrupted flow of water from the pump.

4. When desired, the flange f and its packing g are to be located on the cylinder F at a point nearer the upper end of said cylinder than is shown in the drawings, in which event the air-chamber S will be correspondingly enlarged.

5. When it is desired for any cause to remove the pistons and valves from the well the pump-rod D' is disconnected from the pump-handle and is allowed to drop down, and the end m of the rod j is screwed into the hole n in the arch N^2 of the ring N' , after which the plate or cover d is removed and the set-bolt I unscrewed. The cylinder F , together with the pistons and valves and rod H , may now all be lifted from the well by the pump-rod, and may all be returned in a manner and order the reverse of those just described.

6. When the pump is in operation water is drawn into the cylinder E through the suction-pipe O , and the water so drawn up is prevented from returning by the valve N . As the pistons are depressed the water passes up through the piston J' , and as the pistons are again raised part of the water is forced into the cylinder F and part out through the discharge-pipe B , the air-chamber S producing a steady flow of water. When the pistons again descend the water is forced from the cylinder E out through the discharge-pipe.

7. Certain features of my invention are applicable, by a few obvious mechanical changes, to pumps in which one cylinder only is employed. One or more of the various features of my invention may be employed alone or together, or in connection with pumps of construction other than that herein described, so far as the same may be applicable.

8. Having thus described my invention, what I claim as new, and desire to secure by Letters Patent, is as follows:

1. In a pump, the standard A , provided with tapered foot B' , in combination with a base provided with cup or recess b , substantially as and for the purposes specified.

2. In combination with a standard, the base C , provided with lug i , located within the base C and under the cap d , and set-screw I and pipe H , substantially as and for the purposes specified.

3. In a pump, the standard A , provided with tapered foot B' , and bolt-holes, in combination with a base provided with cup or recess b , and the bolts b' , located in the bottom of said cup and foot, substantially as and for the purposes specified.

4. The combination of the standard A , provided with foot B' , and the base provided with cup b and the opening D , and cap d , substantially as and for the purposes specified.

5. The cylinder E , connected to the lower end of the discharge-pipe B , and provided with a flaring upper end, in combination with the cylinder F , having surrounding collar or flange f , provided with packing g , the said flange being located at some point above the lower end of cylinder F , to permit the latter to extend some distance into the upper end of the cylinder E , substantially as and for the purposes specified.

6. The cylinder E , connected to the lower end of the discharge-pipe B , and provided with a flaring upper end, in combination with the cylinder F , having annular collar or flange f , provided with packing g , the said flange being located at some point above the lower end of said cylinder F , and the studs or flange g' , substantially as and for the purposes specified.

7. The cylinder E , connected to the lower end of the discharge-pipe B , in combination with the cylinder F , said cylinders being constructed substantially as described, and held in position with relation to cylinder E by the pipe or rod H and set-bolt I , substantially as and for the purposes specified.

8. The cylinder E , rigidly connected to the lower end of the discharge-pipe by means of the projection e , located on said cylinder, in combination with the cylinder F , rigidly connected to the pipe H by means of projection G , said pipe H being at top held in position by a setting device, as bolt I , and the said cylinder F held in position in relation to cylinder E by the pipe or rod H and said setting device, substantially as and for the purposes specified.

9. The combination of a pump-cylinder, F , and the actuating pump-rod with the rod H , rigidly attached to said cylinder, and the clamp P , clamped on the rod H , and serving as a guide for the pump-rod and for enabling all to be together withdrawn from the well, substantially as and for the purposes specified.

10. The combination of the cylinder E and the cylinder F , provided with flange f , and suitable packing, as g , and the air-chamber S , substantially as and for the purposes specified.

11. A pump-piston having a rod, j , its lower end projecting below the bottom of the piston, and provided with a screw-thread, in combi-

nation with a valve located in the cylinder, below the piston, said valve being provided with an opening having a female screw-thread for engaging the end of the rod *j*, substantially as and for the purposes specified.

12. The cylinders *E F*, constructed substantially as described, in combination with pistons *J J'*, connected to the pump-rod *D'*, and the valve *N*, connected to the ring *N'*, having arch *N²*, the lower end of the lower piston being provided with the screw-projection *m*, and the arch *N²* with the screw-hole *n* for receiving said projection, substantially as and for the purposes specified.

13. The cylinder *E*, having the contracted lower end, *R*, and rounded shoulder *t*, in combination with the ring *N'* and packing *R'*, said ring and packing being provided with a rounded lower rim, substantially as and for the purposes specified.

14. A pump cylinder having the contracted

lower end, *R*, a rounded shoulder, *t*, being interposed between said contracted portion and the remainder of the cylinder, in combination with the valve having packing whose periphery is straight for a portion of it and above said straight portion increased in diameter, substantially as and for the purposes specified.

15. The combination of the standard *A*, provided with foot *B'* and with the flange *b²*, and the base provided with cup *b*, and the opening *D*, and cap *d*, substantially as and for the purposes specified.

16. In a pump, the standard *A*, provided with tapered foot *B'*, and the flange *b²*, in combination with a base provided with cup or recess *b*, substantially as and for the purposes specified.

BENJAMIN C. VANDUZEN.
